UNITED STATES PATENT OFFICE.

WALTER J. WODRASKA, OF NEW YORK, N. Y.

PNEUMATIC ACTION.

1,396,492.

Specification of Letters Patent.

Patented Nov. 8, 1921.

Application filed June 26, 1920. Serial No. 391,856.

To all whom it may concern:

Be it known that I, WALTER J. WODRASKA, a citizen of the United States, and a resident of the city of New York, borough of Manhattan, in the county and State of New York, have invented a new and Improved Pneumatic Action, of which the following is a full, clear, and exact description.

This invention relates to pneumatic actions for musical instruments or the like, and has particular reference to attachments of this character for automatic player pianos.

Among the objects of the invention is to improve the details of construction, having reference to the valve chests and the valve mechanism therein, the arrangement or disposition of the pneumatics with respect to the valve chests so as to conserve space to the best possible advantage, and to improve the operative connections between the pneumatics and the key operating mechanism.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical transverse section on approximately the line 1—1 of Fig. 2.

Fig. 2 is a horizontal section on the line 2—2 of Fig. 1.

Fig. 3 is a side elevation of that part of the mechanism that would be visible from the plane indicated by the line 3—3 of Fig. 1.

Fig. 4 is a detail perspective view of the adjustable stop fitted to the abstract.

Fig. 5 is a partial end elevation of a modified arrangement of the pneumatics.

Fig. 6 is a diagrammatic side elevation indicating the relation of the valve blocks and pouch boards to one another and the main vacuum casing.

Referring now more specifically to the drawings I show a construction involving the use of a casing 10 having a vacuum space 11 therein, the vacuum being determined and maintained by any approved means with which I am not concerned at this time. The casing 10 includes a top plate 12 into which

the air ducts 13 lead from the tracker board, not shown, through individual ports 14 in the plate 12 and communicating ports 15 in the upper portion of the casing proper. The 60 flexible tubes 16 serve to establish communication between the ports 15 and superposed valve blocks 17 located within the vacuum space, which vacuum space is divided into three independent valve housing chambers 65 by means of the vertical partitions 17', as illustrated in Fig. 6. In each valve block 17 are arranged vertically movable valve devices each comprising upper and lower valves 18 and 19 fixed to the same stem 20 70 and adapted to coöperate in alternation with the upper and lower valve seats 21 and 22 respectively. To the lower end of each valve stem is fixed a head 23 coöperating with a flexible diaphragm 24 spanning the vacuum pit 25 formed in a pouch board 17' spaced below each valve block 17 and from which a bleed port 26 leads to the main vacuum space. In the normal position the valve 19 is seated downward upon the seat 22 closing 80 the passageway through the valve seat and preventing communication between the vacuum space and the air chamber 27 of the valve casing. Atmospheric pressure obtains normally within each pneumatic 28^a or 28^b 85 by reason of the ports 29 and 30 to and from the air chamber 27. At this time the valve 18 is spaced downward below the valve seat 21 so that the air pressure is the same on both sides of the valve 18. When, however, 90 the condition of vacuum is broken in the pit 25 by the admission of a jet of air downward through the ports 13, 14, 15 and 16, the diaphragm acting through the head 23 lifts the valve stem and so unseats the valve 19 95 and closes the port at the valve 18, thus the air pressure within the pneumatic is exhausted through the valve seat 22 into the vacuum space 11. As soon as the port 13 is closed again at the tracker board equilibrium of pressure will be restored on opposite sides of the diaphragm 24 by means of the bleed 26 and the force of suction acting upon the valve 19 will reseat it upon the seat 22. This arrangement of the valve blocks and 100 valves therein is exceedingly simple and they may easily be inspected or repaired if necessary by simply first removing the side plate 31 of the vacuum chest or casing. By arranging the pneumatics one in vertical position and the other in horizontal position 110 across the bottom of the casing space is con-

served, a feature of very great structural importance in musical instruments. The pneumatic 28^a collapses to the right toward the valve casing while the other pneumatic of each pair collapses upward.

A bar 32 constitutes a fixed portion of the structure and to this bar are secured pairs of flanges 33^a and 33^b to which are severally pivoted at 34 a bell crank 35 and 10 an arm 36. Each bell crank is connected to a pneumatic 28^a by means of a link 37 and pivot block 38. The arm 36 is pivotally connected to each pneumatic 28^b through a link 39 and a pivot block 40. The forward 15 end of each lever element 35 or 36 is rounded and faced as shown at 41 with felt or its equivalent for coöperation with a stop member 42 shown in detail in Fig. 4 and comprising a hollow body 43 embracing any 20 suitable part of the key mechanism such as the abstract 44 and having a lug 45 extending into contact with said bearing surface 41. The upper end of the abstract is pivoted at 46 to the wippen 47 which in turn 25 is pivoted at 48 to a flange 49. The lower portion of the abstract is pivoted at 50 to a flange 51 through a link 52. A stop member 53 coöperates with the lower end of the abstract to limit its downward movement. 30 The main portion of the stop 42 is made preferably from a single piece of sheet metal or the like, the lug portion 45 being an extension from the body portion and being of sheet material adapts itself readily 35 to the form of a spring tongue 45' which has direct contact with the arm or lever mechanism. The body portion is wider than the abstract and in the spacing thus provided is arranged a leaf spring 54 fixed to the side 40 of the body at 55 remote from the lug 45. One end, preferably the upper end, of this spring is provided with a knife edge 54' which has a biting action along one edge or face of the abstract so as to render it prac-

tically impossible for the stop 42 to become 45 misplaced along the abstract, while the lower end of the spring is adapted to glide freely downward during the adjustment of the stop by the operator to adapt it to the desired part of the abstract. The downward 50 movement of the levers and arms 35 and 36 is limited by means of a locking bar 56 hinged at 57 to the edge of the bar 32. The weight of the key operating mechanism including the abstract and parts attached 55 thereto insures the prompt return of the pneumatics to the normal position indicated in the drawings after each actuation of the valve mechanism.

I claim:

1. In a pneumatic action for player pianos, the combination with a main casing and a plurality of pneumatics carried thereby and arranged in pairs, one pneumatic of each pair being arranged vertically and the other horizontally, of key actuating means including a bell crank for each vertically arranged pneumatic, and an arm for each horizontally arranged pneumatic.

2. A device of the nature set forth in claim 1 in which the bell cranks and arms are pivoted coaxially of one another.

3. A device as set forth in claim 1 in which the key actuating ends of the levers and arms are all arranged in alignment with one another.

4. In a device as characterized in claim 1 in which the valves for actuating the horizontally and vertically arranged pneumatics are superposed within the main casing 80 thereof.

5. In a device as characterized in claim 4 in which the main casing is divided into a plurality of valve housing chambers and in which a cover plate is respectively provided for each valve chamber.

WALTER J. WODRASKA.
